UNITED STATES PATENT OFFICE

119,257

DESIGN FOR A BEVERAGE TUMBLER OR THE LIKE

Theo Rossi di Montelera, Turin, Italy

Application June 13, 1939, Serial No. 85,474

Term of patent 14 years

To all whom it may concern:

Be it known that I, Theo Rossi di Montelera, a subject of the King of Italy residing at Turin, Italy, have invented a new, original, and ornamental Design for a Beverage Tumbler or the like, of which the following is a specification, reference being had to the accompanying drawing, forming part thereof.

The figure is a perspective view of a beverage tumbler or the like showing my new design.

What is claimed is:

The ornamental design for a beverage tumbler or the like, as shown.

THEO ROSSI di MONTELERA.
